(57) **CLAIM**

An ornamental design for a cap for a blood collection tube, as shown and described.

DESCRIPTION

FIG. 1 is a front elevational view of a cap for a blood collection tube, showing our new design;

FIG. 2 is a rear elevational view thereof;

FIG. 3 is a right side elevational view thereof, with the left side elevational view being identical thereto;

FIG. 4 is a top plan view thereof;

FIG. 5 is a bottom plan view thereof;

FIG. 6 is a perspective view thereof;

FIG. 7 is a cross sectional view taken along line 7-7 of FIG. 4;

FIG. 8 is a perspective view of a blood collection tube with the cap attached;

FIG. 9 is a top plan view of a stopper member of the cap, the stopper member shown separately for ease of illustration;

FIG. 10 is a front elevational view thereof;

FIG. 11 is a right side elevational view thereof;

FIG. 12 is a perspective view thereof; and,

FIG. 13 is a bottom plan view thereof.

The blood collection tube shown in broken lines in FIG. 8 does not form part of the claimed design.
